UNITED STATES PATENT OFFICE.

FRANK I. WEBB, OF MCKEESPORT, PENNSYLVANIA.

AIR-GENERATOR.

1,274,478.

Specification of Letters Patent. Patented Aug. 6, 1918.

Application filed December 5, 1917. Serial No. 205,549.

To all whom it may concern:

Be it known that I, FRANK I. WEBB, a citizen of the United States, residing at McKeesport, in the county of Allegheny and State of Pennsylvania, have invented certain new and useful Improvements in Air-Generators, of which the following is a specification.

This invention has relation to power generators, and has for an object to provide a machine for generating power by utilizing the upward draft which is created in any vertical column when the air within the column is heated.

Another object of the invention is to provide a machine embodying a rotary turbine element constructed in a manner to provide the greatest amount of working efficiency when operating under the influence of the light upward air pressure in a column of the character noted above.

A still further object of the invention is to provide means in a power generator having the above named characteristics for permitting the gradual application of power to the machine or the machinery to be operated whereby to obviate the necessity of reducing the normal speed of rotation of the turbine element when such application of power is made.

A still further object of the invention is to provide means in a power generator of the character above described for preliminarily initiating an upward draft in the column whereby the turbine element may be set in motion and its inertia overcome.

In addition to the foregoing my invention comprehends improvements in the details of construction and arrangement of the parts to be hereinafter more fully described and particularly set forth in the appended claims.

In the accompanying drawings in which similar and corresponding parts are designated by the same characters of reference throughout the several views in which they appear:

Figure 1, is a view in side elevation of the elements of my machine with parts broken away to show details.

Fig. 2, is a view of the machine in plan.

Fig. 3, is a fragmentary detail view in section illustrating the configuration of the blades of my improved turbine wheels, and

Fig. 4, is a detail section taken on the line 4-4 of the preceding figure.

The object of my invention is to provide

a method and machine for generating power whereby the greatest efficiency is obtainable calculated on a basis of fuel consumption. According to recent calculations only approximately 25 per cent. of the heat developed by the combustion of coal is converted into its mechanical equivalent of power through the medium of a steam boiler and high efficiency steam engines. Operating by means of my machine to be presently described, the efficiency or output of the machine relative to the input or quantity of fuel consumed approaches the 100 per cent. mark very closely.

My object is attained through the utilization of the upward draft which takes place in any vertical column when the air within the column is elevated to a temperature slightly above the temperature of the surrounding air, exteriorly of the column. At the present time, the knowledge of chimneys and chimney drafts is slight, and the theories given are worth but little as they are based upon data which is entirely insufficient. As to the design and proportion of chimneys, there are no systematic statements or rules that can be used. Chimneys are usually designed from empirical formulas or from tables compiled from proportions of chimneys that have furnished sufficient draft, etc. The draft produced in a chimney is due to the difference in temperature, and consequent difference in pressure, inside the chimney and the air outside. The gases in the chimney being lighter rise toward the top and air rushes in at the bottom to fill the space left by the hot gases. This air as it becomes heated grows lighter and rises, thus a continuous circulation is kept up. The velocity of a current of heated air in a chimney 100 ft. in height, in feet per second, is given in the table below:

10.

External air.	Air at base of chimney			
	150°	250°	350°	450°
	Feet.	Feet.	Feet.	Feet.
60°	19	26	29	32
70°	18	25	29	32
80°	17	24	28	32

It will be noted that with a difference in temperature between the external air and air within the chamber of only 90° a draft flowing at the rate of 19 feet per second is obtainable. That a temperature of 90° is easily obtainable with the expenditure or

combustion of a very small quantity of fuel is perfectly obvious, and it will be presently seen that a current of air may be utilized to convert itself into mechanical energy for useful purposes.

With reference to the drawings, 10 indicates a column or chimney vertically disposed, and provided with a lateral opening 11 at a point elevated above its base, and 10 a separate opening 12 slightly below the first opening. A substantially semicircular casing 13 is placed with its flat side in registration with the opening 11 and secured to the column or chimney by means of a circumferential flange 14 provided upon the casing. A shaft 15 extends transversely through the casing and carries in fixed engagement therewith interiorly of the casing a turbine wheel 16 of specific construction. 20 The turbine wheel comprises a central hub portion 17 mounted on the shaft and provided with a plurality of peripheral substantially radial recesses in which buckets or blades 18 are held by means of extensions 19 integrally formed upon the buckets for insertion in the recesses. As will be seen from Figs. 3 and 4 of the drawings, each bucket is in the nature of a shell curved longitudinally on an arc which is struck upon 30 a radius equal to two thirds the radius of the turbine wheel. Each bucket is also curved transversely whereby to define a semicircle at the point of greatest depth of the bucket as will be seen from Fig. 4. The buckets are closely spaced so as to permit the inclusion of as large a number as possible in the circumference of the wheel without crowding them too much so as to cause the air to be banked up within the 40 spaces between the blades which would materially decrease the efficiency of the device. A gear 20 is mounted upon the shaft 15 exteriorly of the casing for meshing engagement with a gear 21 slightly smaller in size which is journaled in a bearing 22 formed upon a fan casing 23 the purpose of which will be presently noted. The gear wheel 21 carries a receptive member 24 of a friction clutch designed for coaction with 50 the penetrative member 25 thereof which is rotatably and slidably mounted upon the shaft 26. The penetrative member is formed with a gear 27 and a hub extension 28 which is formed with an annular groove to receive 55 one end 29 of a shipper lever 30 whereby the clutch members may be engaged or disengaged at will. The gear wheel 20 is likewise provided with a central enlargement 31, grooved to receive one end of a shipper lever 32 whereby the gear may be moved into or out of engagement with the gear 21.

A shaft 33 is journaled in the fan casing 23 to extend transversely thereacross and one member 34 of the clutch is fixedly secured 65 thereto for coaction with a member 35 hav-

ing a pinion 36 formed therein which is in constant meshing engagement with the gear 21. An annular groove 37 is formed in the clutch member 35 whereby one end of the shipper lever 38 may be engaged therein to 70 move the clutch member actually into or out of engagement with the clutch member 34 whereby to lock the pinion 36 to the shaft of the fan casing. A plurality of fan blades are mounted on the shaft within the casing 75 whereby to direct air through a peripheral and tangential extension 39 of the casing which extends through the opening 12 of the column to a point directly beneath the turbine wheel. 80

A shaft 40 is mounted on the fan casing for convenience and is disposed parallel to the shafts 26 and 33 and a pinion 41 is loosely mounted thereon for constant meshing engagement with the pinion 36 of the 85 fan shaft. The gear 41 carries a central enlargement 42, grooved to receive one end of a shipper lever 43 whereby the gear may be shifted, the central enlargement 42 being formed with a clutch face to engage a similar clutch face 44 formed on the face of a gear 45 which is also loosely mounted on the shaft 40. A drum 46 is fixed to the gear wheel 45 for rotation therewith, and contains a spiral spring 47, one end of which, 90 preferably the outer end, is connected to the drum, while the inner end is connected to the shaft 40. A ratchet wheel 47 is mounted on the side of the drum to rotate therewith and is engageable by a pawl 48, which may 100 be pivotally mounted on an adjacent stationary support. A pinion 49 is mounted on the shaft 40 for meshing engagement with an idler pinion 50 which in turn is mounted for meshing engagement with a power gear 105 wheel 51. A pawl 52 is mounted to engage, when desired, the periphery of the power gear 51, but is normally held out of such engagement by means of a gravity handle 53 when the machine is in operation. 110

In operation, the turbine wheel is rotated under the influence of the upward draft in the air column whereby its motion is transmitted through the gear 20 to the gear 21 when said gears are in meshing engagement. The power may be transmitted ultimately to the last gear 51 in the train by shifting the lever 30 so as to engage the members 24 and 25 of the clutch operated thereby, whereby the motion is transmitted 115 from the pinion 27 forming a part of the clutch to the gear 45. The spring 47 within the drum being detensioned at that time, the spring is wound up by rotation of the gear 45 without rotating the shaft 40 upon 120 which the drum is mounted, until the spring has been thoroughly tensioned whereupon the power will be transmitted to the shaft 40 through the spring and rotation is continued through the gears 49 and 50 to 125 130

the gear 51, the latter serving to apply power to any means desired to be given. The pawl 52 during this operation should obviously be out of engagement with the gear wheel 51. The pawl 48 being in engagement with the ratchet 47 prevents backward rotation of the drum and consequent detensioning of the spring. The spring 47 thus provides in effect a shock absorber or means to permit the gradual application of power to the means to be driven without interrupting the normal speed or rate of rotation of the turbine wheel.

When the machine is to be stopped, before the motion of the train of gears has ceased, the pawl 52 is thrown into engagement with the gear 51 whereby rotation thereof is precluded. It will be obvious that pawl 48 being in engagement with the ratchet 47 and the drum, the spring 47 will be held under tension when the turbine wheel ceases rotation. Power is thus stored in the spring, and may be utilized to serve as a means to start the turbine wheel and overcome its inertia provided the upward draft of the air column is insufficient for that purpose. To this end the gear 20 is shifted to disengage the same from the gear 21, and while the clutch members 24 and 25 are out of engagement the clutch lever 37 is oscillated to throw the clutch members 34 and 35 into engagement likewise the clutch members 42 and 44. The pawl 48 is then disengaged from the ratchet 47 whereupon the spring within the drum is released and a drum will be rotated in a direction reverse from its normal direction of rotation, and the motion of the same will be transmitted to the gear 41 having been connected thereto by shifting of the lever 43, whereupon the pinion 36 of the fan shaft will be rotated, and a current of air will be thrown into the air column in an upward direction, thereby rotating the turbine wheel so as to overcome its inertia. The turbine having thus been set in motion its motion will be continued by the upward draft in the column. It will be apparent that if the gear 20 of the turbine shaft is thrown into engagement with the gear 21 while the clutch members 34 and 35 are in engagement, the turbine wheel and fan will be connected for rotation in unison.

From the foregoing, it will be apparent that if the turbine wheel 16 is 6 feet in diameter, and the flow of air in the column is at the rate of approximately 19 feet per second, the peripheral velocity of the wheel, owing to the fact that the blades of the wheel are so designed as to give a maximum efficiency of very nearly 100 per cent, will be the same or approximately 19 feet per second making a speed of rotation of sixty revolutions per minute. This speed of rotation it will be noted is effected merely by a difference in

temperature of 90° at the base of the column. It will therefore be apparent that calculating on a basis of fuel consumption, a maximum amount of energy is obtainable by this upward draft method for propelling machinery, provided the machinery is designed with a view to obtaining a maximum efficiency of operation. If the walls of the column are made of double thickness with a dead air space therebetween, the radiation of heat from the interior of the column will be reduced whereby the energy obtained per unit quantity of fuel consumed can be materially increased.

It will be apparent that this machine may be embodied in any chimney, as for instance chimneys for creating drafts under steam boilers whereby the current of air always present in the chimney could be utilized to a good purpose to drive machinery. The illustration given however, is under the assumption that the column is designed especially for use in connection with my machine herein disclosed and the current of air is created by means of a source of heat provided entirely for that purpose.

While I have illustrated and described my invention with some degree of particularity, I realize that in practice various alterations thereover may be made, and I therefore desire to reserve the right and privilege of changing the form of the details of construction, or otherwise altering the arrangement of the correlative parts without departing from the spirit of the invention or the scope of the appended claims.

Having thus described my invention what I claim as new and desire to secure by Letters Patent is:—

1. In a power generator, the combination of a vertical tube open at its lower end, a turbine wheel mounted to extend partly within the tube, a blower for creating an upward current of air within the tube to initially start rotation of the turbine wheel to overcome its inertia, a spring motor for rotating the same, and means operable by rotation of the turbine for winding up the motor.

2. A power generator including a vertical column, a turbine wheel mounted therein, a gear operable by rotation of said turbine wheel, a second gear in meshing engagement with the first, a clutch member carried by said second gear, a third gear, a clutch member carried by said third gear for meshing engagement with the other clutch member, a fan having an outlet extending into the column, a shaft operating said fan, a pinion loosely mounted on said shaft, clutch members for connecting said shaft with the pinion, said pinion being in meshing engagement with the second gear, a spring drum, a fourth gear carried by the spring drum, in meshing engagement with the third gear, a

5 fifth gear in meshing engagement with the pinion, clutch mechanism for connecting said fourth and fifth gears, reduction gears operable by rotation of said spring drum, and releasable pawls to engage the reduction gear and the spring drum to prevent rearward rotation thereof.

In testimony whereof I affix my signature in presence of two witnesses.

FRANK I. WEBB.
